UNITED STATES PATENT OFFICE.

ALEXANDER MAGEE AND DAVID C. LEE, OF ST. LOUIS, MISSOURI; SAID MAGEE ASSIGNOR TO SAID LEE.

WASHING-MACHINE.

SPECIFICATION forming part of Letters Patent No. 359,933, dated March 22, 1887.

Application filed November 17, 1884. Serial No. 148,134. (No model.)

To all whom it may concern:

Be it known that we, ALEXANDER MAGEE and DAVID C. LEE, of St. Louis, Missouri, have jointly made a new and useful Improvement 5 in Washing-Machines, of which the following is a full, clear, and exact description.

The improvement relates to that class of washing-machines having an inner perforated case and an outer closed case, the inner case 10 being adapted to hold the clothes being washed and to be rotated within the outer case, which is adapted to contain the water used in the washing.

The annexed drawings, making part of this 15 specification, exhibit the mechanism employed in carrying out the improvement.

Figure 1 is a plan of the improved washing-machine, the cover of the outer casing being removed. Fig. 2 is a vertical longitudinal section on the line 2 2 of Fig. 3, and Fig. 20 3 is a vertical transverse section on the line 3 3 of Fig. 2.

The same letters of reference denote the same parts.

25 A represents the outer case. Its lower part, a, is adapted to hold water, and by means of the cover a' the case can be closed.

B represents the inner case. By means of the journals b b, with which the inner case is 30 provided, and the crank b' the inner case can be rotated in the outer case. The bearings a² a² for the journals b b are preferably in the upper edge, a³, of the lower part, a, of the outer case. A portion, b², of the inner case is 35 made to open and close, or otherwise made removable, so that the articles to be washed can be inclosed within the inner case and when washed removed therefrom.

The distinguishing features of the present 40 washing-machine are these:

First. The face b³ of the inner case is made of wire-gauze, by reason of which steam arising from the water in the bottom of the outer case can freely penetrate the inner case.

45 Second. The inner case is provided with one or more "water-elevators," b⁴, as they may be termed. Their function is to lift the water to above the center of the inner case, and then discharge it onto the articles within the case—

that is, the water-elevators are attached to and 50 are rotated with the inner case, and when, in the rotation of the inner case, they are carried downward into the lower part of the outer case they become filled with water, and when they are carried upward above the center of the inner case the water is emptied from them. To this end the most desirable mode 55 of constructing and attaching the water-elevators is that shown. A sheet of metal is shaped into the elliptical or approximately 60 elliptical form (in cross-section) shown in Fig. 2, is extended endwise across the inner case to meet its imperforate sides b⁵ b⁵, and thereby or in some other suitable manner closed at its ends, and is fastened to the face b³ of the inner case. The water-elevator is thus closed, 65 saving at the openings b⁶ and at the slot b⁷, respectively on opposite sides of the elevator and in coincidence with a radial line of the inner case. The water enters the elevator 70 through the outer openings, b⁶, and it leaves the elevator through the slot b⁷. In the class of washing-machines under consideration the water enters the inner case but a slight distance, not coming in practice above the upper side of the water-elevators at their lowest 75 level as they are carried around with the inner case. The water-elevators are useful, then, in that thereby a flow of water downward upon and through the articles being 80 washed is allowed. The steam, which, by means of the wire-gauze face b³, enters freely all parts of the interior of the inner case, is mainly instrumental in loosening the dirt, and the water-flow described serves to carry the 85 loosened dirt away.

Third. The bail C, which is attached to the journals b b of the inner case. By means of it the inner case, with its contents, can be readily lifted from its place in the outer case 90 and transferred to where it is desired to deposit the washed articles. Then, removing the cover and still holding the case B by the bail, the case, by means of the crank, can be rotated in the bail, so as to bring the opening 95 downward, whereupon the articles can be dropped from the case.

Fourth. It is undesirable to allow any steam

to escape at the joint between the cover and lower part of the outer case. Therefore in the present instance this joint is made as tight as is readily practicable, and at the top of the outer case-cover is a perforation, a^4 , through which the steam can escape in small quantities; but to prevent the too free escape of the steam a valve in the form of a ball, a^5 , is adapted to seat at and close the opening, saving when it is unseated by an undue pressure of steam. A suitable guard, a^6 , keeps the ball in the immediate vicinity of the perforation a .

We are aware that in washing-machines of the class under consideration closed cylinders having water-elevators have been used, as well as open-faced cylinders without any provision for raising the water. We therefore do not claim such constructions; nor would either of them answer our purpose, which is to provide, first, for loosening the dirt from the clothes, (accomplished by the steam circulating through the open-work face,) and, second, for carrying away the loosened dirt, (accomplished by the elevated water.)

We claim—

1. In a washing-machine, the combination of an outer case, an inner case journaled therein, removable therefrom, and having an opening or door, b^2 , a bail, C, having bearings which surround the journals of the inner case, and a crank or handle, b' , attached to one of the journals, by which the inner case may be rotated to perform the washing action or to discharge the contents by the opening b^2 when removed and supported by the bail, substantially as set forth.

2. In a washing-machine, the combination of an outer case, an inner reticulated case, B, journaled and removable, as described, and having water-elevators and an opening, b^2 , a bail, C, having bearings which support the case B, and the handle b' , substantially as set forth.

ALEXANDER MAGEE.
DAVID C. LEE.
